UNITED STATES PATENT OFFICE

170,664

BOWLING GAME DEVICE

Howard F. Spear, Greenview, Ill.

Application May 26, 1952, Serial No. 19,892

Term of patent 14 years

(Cl. D34—5)

To all whom it may concern:

Be it known that I, Howard F. Spear, a citizen of the United States and a resident of the town of Greenview, county of Menard, and State of Illinois, have invented a new, original, and ornamental Design for a Bowling Game Device, of which the following is the specification, and reference being had to the accompanying drawing, forming a part thereof.

Fig. 1 is a perspective view of a bowling game device, showing my new design;

Fig. 2 is a top plan view thereof to a reduced scale;

Fig. 3 is a side elevational view thereof, to a reduced scale; and

Fig. 4 is a front elevational view thereof, to a reduced scale.

I claim:

The ornamental design for a bowling game device, as shown.

HOWARD F. SPEAR.
